UNITED STATES PATENT OFFICE.

WALTER G. JOY, OF CLEVELAND, TEXAS.

RAILWAY GATE AND SIGNAL.

Application filed May 21, 1925. Serial No. 31,903.

To all whom it may concern:

Be it known that I, WALTER G. JOY, a citizen of the United States, residing at Cleveland, in the county of Liberty and State of Texas, have invented certain new and useful Improvements in Railway Gates and Signals; and I do hereby declare the following to be a full, clear, and exact description of the invention, such as will enable others skilled in the art to which it appertains to make and use the same.

This invention relates to a railway gate and signal.

It is an aim of the present invention to provide a cautionary signal for use or actuation at a railway crossing prior to the closing of the gate in the interest of safety.

Another object is to provide a novel construction of gate wherein the operating pull will not be direct thereon but on the contrary will be shiftable, and also a gate having a shiftable weight means to aid in maintaining it in both open position or closed position as the case may be.

Another object is to provide a novel construction wherein the gate and the signal are under control for automatic operation by the rolling stock, usually the locomotive.

More specific objects and advantages will be pointed out in part and otherwise become apparent from a consideration of the description following taken in connection with accompanying drawings illustrating an operative embodiment.

In said drawings:

Figure 1 is a view of the device in plan;

Figure 2 is a view thereof in side elevation with the parts in open position, the signal being shown in closed position in dotted lines;

Figure 3 is a side elevation showing the gate in closed position;

Figure 4 is a rear view looking towards the gate;

Figure 5 is a cross sectional view taken on line 5—5 of Figure 1, showing the mounting of the signal;

Figure 6 is a diagrammatic longitudinal section showing the control of the various cables, gate and signal;

Figure 7 is a perspective view of one of the cable operating levers;

Figure 8 is a longitudinal sectional view illustrating the shiftable weight means of the gate.

Referring specifically to the drawings, a

railway track of conventional form is suggested at 10 and a road crossing thereover is indicated at 11 and has a gate in the nature of a bar 12, or of other construction, associated therewith. This gate is located at one side of the crossing while at the other side of the crossing a signal in any desired form is provided which may be a lever arm or semaphore 13.

The gate or bar 12 has a fulcrum rod 14 journaled in bearings 15 at the top of suitably mounted posts 16, in spaced relation, and between which the gate operates. Said rod 14 may be arranged in any one of a series of openings 17 provided in the gate bar 12 in order to balance the same or afford more efficient operation in connection with a weight means hereinafter disclosed. A connecting rod or member 18, for operating cables, is disposed angularly with respect to the gate and at each end is pivotally connected as at 19 to links 20, differing in size, and which at 21 are pivoted to the gate.

Cables 22 and 23 are connected to opposite ends of rods 18 and the latter cable may have an extension 24 directly connected to the gate as shown. These cables are of any suitable flexible construction and are trained over pulleys 25 journaled on rods 26 fastened to the posts 16. The cable 22 is also fastened to a rocker shaft or lever 27, suitably journaled in and carried by a housing 28 located in the road bed. Cable 22 is directly connected to an arm 28 of said lever 27. Said lever also has an upstanding lug 29 arranged in the path of advance of the rolling stock which travels on the track 10 and being adapted for engagement by a dependent member 30, on said rolling stock, in order to rock the lever. The gate in Figure 2 is shown in its elevated or open position as contrasted with its closed position of Figure 3. The gate has associated with it, means to maintain it in either of the open or closed positions against accidental displacement. Such means consists of an inclined tube 31 forming a passageway in which balls 32, functioning as weights, are adapted to travel. Said balls are located at opposite ends of the tube, according to the position of the gate, in one position thus being on one side of the fulcrum of the gate and in the other position being on the opposite side of such fulcrum. Said gate in its lowered position rests on a transverse support 33 of any desired construction but in

this instance being mounted by spaced posts 34.

The lever or semaphore 13 is pivoted on a rod 35 spanning two of the posts 34. This 5 arm at the crossing end is preferably formed into a disk as shown having "Stop" delineated thereon. Two cables 36 and 37 are fastened to the signal arm or semaphore 13 one on each side of its fulcrum and are 10 trained over pulleys 38 journaled on rods 39 spanning certain of the posts 34. This signal 13 is normally urged to an elevated position by means of a weight 40 carried at one end thereof. A pull on the cable 36 will 15 lower the signal arm 13 and the latter will be limited to lowered position by a transverse bar or support 41 spanning the adjacent posts 34. Cable 36 is fastened to an arm 42 of a rock shaft or lever 43, similar to 20 the lever 27 and journaled in a suitable housing 44 and having an upstanding lug 45 thereon similar to the lug 29 and adapted for engagement by the dependent 30 so as to lower the signal 13 to apprise 25 pedestrians or traffic of the approach of the train, before lowering of the gate and thus being arranged a greater distance from the gate than the arm 29.

Both the gate 12 and the signal 13 are 30 adapted to be restored to open position simultaneously by the train after it has passed the crossing and to this end, another rock shaft or lever 46, similar to those at 27 and 43, is used. This lever 46 is journaled in a 35 suitable housing 47 and has an operating lug 48 for engagement by the dependent 40 similarly to the lugs 29 and 45. Said lever has an arm 49 from which a cable 50 extends which is connected to arms 51 and 52 of the levers 27 and 43, respectively. Said cable 50 is trained over suitable guide pulleys 53 and the pulleys are located within housing 54, including tubes 55 connected to the housings 28, 44 and 47 and constituting 45 guides for the various cables and permitting such cables to be used even on curves as well as straight tracks. The cable 50 upon being tensioned through the manipulation of lever 46, restores the gate and signal or 50 semaphore 13 to normal or raised position.

It is to be realized that the semaphore 13 may be of any size desired and that it does not project over the crossing a distance sufficient to interfere with traffic.

55 Presuming the parts operatively connected with a track and the gate and semaphore 12 and 13, respectively in open position, upon the approach of a train, the dependent member 20 first engages the lug 45, thus 60 rocking lever 43 and causing the cable 36 to lower the signal 13. This will apprise traffic of the fact that a train is approaching and that the gate 12 is about to lower. At 65 the desired time interval, governed by the distance levers 43 and 27 are spaced, the

dependent member 30 engages the lug 29, rocking lever 27 and through the movement of cable 22, lowering the gate. During the movement to this position, the balls or weights 32 shift toward the signal 13 where- 70 by they are located in such a position as to prevent accidental movement of the gate. After the train has passed, it will through the medium of dependent member 30 engage lug 48, thus rocking lever 46 and exerting 75 such a pull on cable 50 as will rock the levers 27 and 43 and cause them, through the connection of the cables 23 and 37 with their arms 51 and 52, respectively, to simultaneously open the gate and raise the signal 80 13. Particular attention is called to the fact that incidental to the operation of the cables 22 and 23, they do not exert a direct pull on the gate since they are connected with the rod 18 and the latter shifts ac- 85 cording to the pull, thus avoiding a direct pull and rendering easier operation of the gate, and reducing the strain on the cables.

Various changes may be resorted to provided they fall within the spirit and scope 90 of the invention.

I claim as my invention:—

1. An apparatus of the class described comprising a gate, means to actuate said gate, and means carried by the gate having a movement relatively to the gate and independently of the swinging movement of the gate and of the first mentioned means to which the first mentioned means is connected to avoid direct operating pull on the gate. 95

2. An apparatus of the class described comprising a gate, a rod carried thereby having a movement relatively to the gate and independently of the swinging movement of the gate, oppositely operable pull cables connected to said rod and adapted for actuation to open and close the gate. 105

3. An apparatus of the class described comprising a gate, a rod carried thereby having a movement relatively to the gate and independently of the swinging movement of the gate, oppositely operable pull cables connected to said rod and adapted for actuation to open and close the gate, posts supporting the gate, and guide pulleys 110 for said cables, means mounting said guide pulleys connected to said posts.

4. An apparatus of the class described comprising a gate, means pivotally mounting the gate, a shiftable weight carried by the gate movable with respect to its fulcrum for the purpose specified, a rod carried by the gate having a movement relatively to the gate and independently of the swinging movement thereof, and means operable by pull to open and close the gate connected to the rod on opposite sides of its fulcrum. 125

5. An apparatus of the class described comprising a gate, a signal operable to in- 130

dicate the movement of the gate, means pivotally mounting said signal, draw elements connected to said signal on opposite sides of its fulcrum, guide means for said draw elements, means pivotally mounting the gate, draw means to operate the gate, guide means for the draw means on the

last mentioned means, track obstacle levers to actuate said draw elements in one direction, and a track obstacle lever operable ¹⁰ to move certain of the draw elements in the other direction.

In testimony whereof I affix my signature.

WALTER G. JOY.
